KEITH CLARK, OF RIDGEWOOD, NEW JERSEY

DESK CALENDAR.

Application filed June 1, 1929. Serial No. 367,676.

The object of the present invention is to provide a simple, inexpensive and easily assembled pad calendar belonging to that type of desk calendar in which a base or platen is held in an inclined position in relation to the top of a desk or other support by suitable legs and on which base there is provided a stack of sheets adapted to be removed from the stack by tearing. There have been several devices proposed for the assembly of the base legs, stack of sheets and tearing plate on pad calendars of the type herein referred to, where provision was made for the removal of the legs in order to permit the pad calendar to be shipped in knocked down or flat position. The object of the present invention is to provide a pad calendar in which the advantage of shipping the device in knocked down or flat condition is sacrificed in order to simplify the construction and assembly of the article and also to avoid the loss of the legs, which has heretofore been one of the disadvantages of the knocked down type of pad calendar. The present device, therefore, comprises the base, legs which are permanently attached to the base by simple means, and screws which pass through holes in the pad, the sheets and tearing plate, and screw into sockets in the legs.

In the drawing forming part of this application,

Figure 1 is a plan view of a pad calendar embodying my invention.

Figure 2 is a side elevation thereof,

Figure 3 is a sectional view taken on the line 3—3 of Figure 1,

Figure 4 is a similar view showing the parts being assembled, and

Figure 5 is an enlarged, vertical sectional view through one of the legs.

Fig. 6 is a side elevation of a modified form of leg.

In the drawing I have shown a pad calendar consisting primarily of a base or platen 1 which forms a rest for the stack of sheets and on which the stack of sheets 2 is adapted to be held in position for convenient writing on the top sheet, and the base and pad are held in an inclined position in relation to the desk top 3 or other support by means of legs 4, prefer-

ably two, arranged adjacent opposite sides and at one end of the base. On the top of the stack of sheets and near the top end thereof there is a tearing plate 5 against the front edge 6 of which the sheets may be torn. It will be understood that in day calendars and similar articles the sheets are removed from the top of the pile from time to time either by tearing against the edge of the tearing plate or by tearing them away from the clamping screws, as will be hereinafter pointed out.

The legs which support the base in elevated position are both alike, so that a description of one will answer for both. The leg consists of a member 4 having a bore 7 extending the major portion of the length of the member and if desired a rubber plug 8 may be inserted in the lower end of this bore, the plug having an enlarged head 9 seating against the end of the leg and forming a cushion member to prevent the leg from scratching the surface of the support on which the device is placed.

When the leg is first made and before it is attached to the base it has a shoulder 10 which in the form of the device shown in Figure 5 of the drawing is made by providing a lateral flange 11 on the leg. In Figure 6 the shoulder 10 is formed by a reduction in diameter of the upper and lower portions of the leg, as shown. The upper end of the leg is provided with a bore 12 the surrounding wall of which is adapted to be upset or rolled. Below this bore 12 there is a sub-bore provided with an internal thread 13 to receive the clamping screw 14.

The tearing plate 5 is provided with apertures to receive therethrough the clamping screws 14 which hold the body in assembled position on the base, the screws shown herein having the external thread 15 and the heads 16. The stack of sheets 2 is also provided with apertures in register with the apertures of the tearing plate, through which the shanks of the screws 14 may pass.

In making up the parts of the pad calendar the legs are permanently attached to the base as follows: The upper portion of the leg 4 is passed through an aperture 19 near one end of the base, so that the wall sur-

rounding the bore 12 projects above the top surface of the base and the shoulder 10 rests against the under surface of the base around the aperture 19. A suitable tool is then inserted into the bore 12 and pressed downwardly, so that the edge of the wall surrounding the bore 12 is upset or rolled until it projects outwardly and is compressed against the top surface of the base and around the aperture 19, in the manner shown at 18 in Figures 3 and 4.

When this operation has been performed, and it may be carried out by simple dies in a press, the legs are permanently attached to the base, the portions of the base surrounding the apertures 19 being gripped between the shoulders 10 and the rolled edge 18. The same operation is performed for both legs or as many as are to be applied to the device. The parts are now ready for assembly. The stack of sheets is placed upon the top surface of the base so that the apertures in the stack of sheets register with the bores of the legs; the tearing plate is placed on the top of the stack of sheets with its apertures registering with the apertures in the stack of sheets; and the shanks of the screws 14 are passed successively through the apertures of the tearing plate, thence through the apertures of the stack of sheets 2 and the end of the shank is screwed into the threaded socket 13 of the leg. The screws 14 may be turned down to cause their heads 16 to press tightly on the tearing plate where it is desired to remove sheets from the stack by tearing against the front edge 6 of the tearing plate, or, if desired, the screws may be slackened off to remove pressure from the stack so that the sheets may be pulled out lengthwise to tear them away from the screws 14 in which case there will be no stubs left from the torn sheets, and the tearing plate 5 will travel down as the sheets are removed from the stack. From time to time the screws 14 may be turned down or screwed further into the threaded sockets 13 as sheets are removed from the stack and the lower bore 7 of the leg is adapted to receive the shank of the screw as the latter is moved downwardly.

From the above it will be apparent that I have provided a pad calendar in which the legs are assembled by a simple and inexpensive method to form a permanent attachment with the base while providing vertically adjustable screws for holding the pad assembled on the base. When the stack of sheets has been consumed it is only necessary to remove the screws 14 and the tearing plate and place a new stack of sheets in position on the base and thereafter return the tearing plate to position and replace the screws. The legs do not have to be detached from the base when a new stack of sheets is to be assembled. As the legs are permanently attached to the base

they are not lost during shipment and it is unnecessary for the consumer to attach the legs to the base as in former devices.

Having described my invention, what I claim is:

1. In a pad calendar the combination of a base having apertures and a stack of sheets supported on said base, legs for holding one end of said base in an elevated position on a support, said legs extending through said base and having portions engaging the inner and outer surfaces of said base around said apertures to secure the legs to the base, said legs having longitudinal bores and screws for extending through the stack of sheets and so threaded into said legs for the purpose of securing the stack of sheets to said base.

2. In a pad calendar the combination of a base having apertures, a stack of sheets supported on said base, and legs for holding one end of said base in an elevated position on a support, said legs extending through the apertures of said base and having a shoulder engaging the bottom surface of said base adjacent the apertures, the upper ends of said legs which project through said apertures being turned outwardly to form flanges for engaging the upper side of said base adjacent said apertures, and screws extending through the stack of sheets and threaded into said legs to secure the stack of sheets to said base.

3. In a pad calendar the combination of a base having apertures, a stack of perforated sheets supported on said base, legs for holding one end of said base in an elevated position on a support, the upper ends of said legs extending through the apertures of said base, said legs having shoulders resting against the under side of said base adjacent said apertures, said legs having longitudinal bores and a sub bore spaced from the upper end of the legs, said legs having their upper ends forced outwardly and downwardly against the upper surface of said base adjacent the apertures of said base and screws extending through the stack of sheets and threaded into said sub bore of said legs and adapted to secure the stack of sheets to said base.

Signed at the city, county and State of New York, this 14th day of May, 1929.

KEITH CLARK.
